UNITED STATES PATENT OFFICE

99,076

DESIGN FOR A GLASS BUILDING BLOCK

Harold L. Eastus, Muncie, Ind., assignor to
Owens-Illinois Glass Company, Toledo, Ohio, a
corporation of Ohio

Application February 12, 1936, Serial No. 61,115

Term of patent 14 years

To all whom it may concern:

Be it known that I, Harold L. Eastus, a citizen
of the United States and residing at Muncie, in
the county of Delaware and State of Indiana,
have invented a new, original, and ornamental
Design for a Glass Building Block, of which the
following is a specification, reference being had
to the accompanying drawing, forming a part
thereof.

In the drawing:

Fig. 1 is a perspective view of a glass building
block showing my design.

Fig. 2 is a sectional view taken along the line
2—2 of Fig. 1 and further illustrating the surface
ornamentations.

I claim:

The ornamental design for a glass building
block substantially as shown and described.

Signed at Muncie in the county of Delaware
and State of Indiana, this 7th day of February,
1936.

HAROLD L. EASTUS.
